UNITED STATES PATENT OFFICE

2,562,793

LUMINOUS SIGN

Arthur Johnson, Roby, near Liverpool, England

Application June 12, 1945, Serial No. 598,931
In Great Britain August 25, 1944

1 Claim. (Cl. 40—52)

1 This invention relates to luminous monogrammatic signs of the type in which letters of the alphabet or other symbols appear successively at one end of the sign and apparently move across the sign to the other end thereof where they successively disappear. And the present invention aims to produce such a sign which, whilst being effective in arresting the attention of passers-by, shall be simple in construction and economical in current consumption; and, being reliable—i. e. not liable to derangement under normal conditions of use—may be operated for prolonged periods at low maintenance cost.

My sign is essentially characterised in that the use of a plurality of electric lamps, to form individual letters of the alphabet, numerals, and other symbols or representations, e. g. smoke rising from a cigarette, a crawling border script-writing, et cetera (all hereinafter, for convenience of reference, designated letter or letters), is obviated, the letters being produced, under my invention, the combination of a non-transparent screen or plate (hereinafter for convenience of reference, designated sign-plate), wherein or whereon are formed appropriately spaced light-emitting apertures of desired shape or configuration, and pivotally mounted plates or shutters (hereinafter, for convenience of reference, designated disc or discs), located on the inside of said sign plate in proximity with and adapted to open and close said light-emitting apertures; electro-magnets the armatures whereof are operatively and individually connected with individual discs, so that when an electro-magnet is energised its armature is caused to raise its connected disc, and when the same electro-magnet is de-energized the disc is permitted to fall to plate-aperture closing position; electrically-illuminable tubes situated behind said plate apertures; contacts individually electrically connected with said electro-magnets; and contacts for permanent connection with the source of electricity supply.

In one "flashing" arrangement, I utilize letters provided with (A) a contact adapted to co-operate with said contacts for connection with the source of electricity supply and (B) contacts in permanent electrical connection with said A contact, and arranged and adapted to select the contacts of certain electro-magnets—according to the sign-letter to be created—for energization and consequential raising of their associated discs to cause the formation of letters built up and flashed by the then opened and so tube-illuminated, apparatus.

2

In another embodiment of my apparatus, I control the contacts electrically connected with the electro-magnets by means of a known form of message-carrying perforated strip adapted to control the current flow by making and breaking electrical connection between said contacts associated with the electricity supply and the contacts associated with the electro-magnets.

Said message-carrying strip may be of the kind commonly employed in apparatus for lamp-flashing news.

As a means of effecting the flashing of the letters from the sign-plate, I may employ contact-carrying letter plates, the conducting contact members whereof being shaped and/or arranged to form the required letters, so that if said contact members of a pre-selected letter plate are placed or moved into engagement with contact members electrically connected with said electro-magnets, the appropriate electro-magnets will be energised to cause, through consequential attraction of said disc-connected armatures actuation of the appropriate discs which, in co-operation, effect the required luminous letter on the sign plate.

Said contact elements electrically connected with the electro-magnets are preferably arranged as a bank of spring metal arms which—to ensure good rubbing contact—are displaced against their spring resistance when letter contacts are placed or passed between same. Each letter plate is provided with a contact knife, or its equivalent, in permanent electrical association with the contact members of the plate, and adapted to engage with and dis-engage from contacts connected with a source of electricity supply simultaneously with the engagement and disengagement of the letter-plate contacts with and from said contacts electrically connected with the electro-magnets.

The means of illumination are electrically-illuminable tubes placed in appropriate—usually horizontal—alignment behind said sign-plate which may constitute the front of a casing wherein the luminous tubes and electro-magnets with their disc actuating connections are disposed. The casing may have light reflective surfaces.

Said light-emitting apertures of an otherwise non-transparent sign-plate, if they consist of through openings in the sign-plate, may be glazed, or fitted with glass lenses; or, alternatively, the sign-plate, as a whole, may be provided with a facing of glass or other suitable transparent material.

55 Alternative to the formation of through open-

ings in a sign-plate made of material—such as sheet metal or a “plastic” composition—which is opaque to light, I may coat or cover a plate of glass, or other transparent substance, say, with paint or fabric, leaving spaces in the coating or covering to provide light-emitting apertures wherewith said non-transparent discs are associated.

In the application of my invention to a flashing sign in which letters successively appear on the right of the sign and apparently travel to the left where they disappear—or alternatively travel vertically or at an inclination—I may utilize a controller including a mechanically driven endless chain or like conveyor, or a drum, and a plurality of letter carrying components whereto letters may be applied in a readily detachable manner and so that in the letters’ travel their contacts will engage, displace and pass certain of said bank of spring contact arms and cause the flashing from the sign-plate of the required announcement time after time for as long as may be desired. An announcement may, of course, be easily changed by re-arrangement of the contact-carrying letters on the conveyor or drum; and, if desired, by stopping the conveyor or drum, the—now stationary—announcement in full will appear.

I will further describe my invention with the aid of the accompanying sheets of explanatory drawings which illustrate, by way of example only, one mode of embodying same.

In said drawings:

Fig. 1 is an end view, partly in section, of a casing provided with an apertured front (sign) plate, and including two of the discs and electro-magnetic means for actuating same.

Figs. 2 and 3 are detached views of a disc; Figs. 4 and 5 are, respectively, plan and elevation of a detached electro-magnet; and Figs. 6 and 7 are detached views of an armature.

Fig. 8 is a front view of a fragment of the sign-plate with letters appearing thereon, and Fig. 9 is an inverted plan of portion of an electro-magnets’ supporting bracket and associated parts.

Fig. 10 is an end view, Figs. 11 and 11a a side elevation, and Fig. 12 a plan of part of an endless chain conveyor, and letter-plates carried thereby in and out of circuit-completing positions.

Fig. 13 is a plan view of some of a stationary bank of contacts.

Figs. 14 and 15 and 16 are, respectively, plan elevation, and inverted view of a letter-plate carrier in letter-holding position; and Figs. 17, 18 and 19 are similar views showing the letter carrier preparatory to receiving a letter.

Figs. 20, 21 and 22 are perspective views of a letter drawn to an enlarged scale as compared with the preceding figures.

In the several views like characters of reference denote like parts wherever they occur.

Referring now to the drawings, I represent a metal sign-plate in which horizontal rows of through apertures 2 are formed; said plate 1 constitutes the front of a casing 3 (mainly indicated by broken lines) and is protected by a sheet 4 of clear or frosted glass.

Disposed on the inner face of said sign-plate 1, and extending horizontally throughout the length thereof are sheet metal brackets 5, these being situated one above each row of apertures 2 of sign-plate 1.

Carried by each bracket 5 is a fulcrum pin or spindle 6 whereon are pivotally mounted—but

so as to normally mask the sign-plate openings 2—discs of metal, or other suitable material, each comprising a flap portion 7 and a hook 8; and linked by an eye extremity with said hook 8 is an armature member 9 of annealed sheet iron, the other end whereof is pivotally mounted on a pin or spindle 10 also carried by said bracket 5 and extending horizontally the full length thereof.

Secured to the underside of each bracket 5 are electro-magnets 11 equal in number to those of a horizontal row of sign-plate apertures 2.

Disposed within casing 3, and extending horizontally behind each row of apertures 2 of sign-plate 1, is a luminous tube 12, said tubes being supported in spring clips 13 mounted on the respective brackets 5.

Normally, a disc 7 assumes a hanging position under the influence of gravity to close its aperture 2 of the sign-plate and so prevent the transmission of light from luminous tubes 12—as illustrated as “A” Fig. 1. When, however, its magnet 11 is energised, armature 9 is attracted—as shown at “B” Fig. 1—with the result that the disc, being linked thereto is pivotally moved about spindle 6 to rise and uncover its plate aperture 2 and permit the emission of light therethrough. Then, when the circuit through the electro-magnet is broken, the disc falls by gravity to obscure the light again. Attached to each bracket 5 is a conducting terminal block 14.

Situated in any convenient position—i. e. remote from the sign proper—is the disc working apparatus which includes a—preferably motor driven—chain type endless conveyor between the chains 15 whereof letter supporting members 16 are movably attached, these being constructed to hold, in a readily detachable manner, letter-plates 17 the contacts 17b whereof are adapted, in the travel of said conveyor, to engage with certain—according to the particular contact arrangement of the letters—stationary spring contact fingers 18 of a bank of fingers carried by an insulated block 19 and secured in position by wedges 20.

Thus, on the contacts 17b of a letter-plate 17 engaging, displacing and passing preselected stationary spring contact fingers 18, the appropriate magnets 11 will be energized and the discs 7 associated therewith actuated to show the letter on sign-plate 1, which letter has been created by certain sequentially illuminated apertures 2, the letter apparently moving along the sign-plate from right to left. When so permitted, the spring contact fingers 18 reassume their positions as before actuation. Each letter-plate 17 is also provided with a contact knife 17d adapted in the travel of the letter-plate to engage with and disengage from a line of stationary spring contact fingers 18a mounted on block 19 and which contacts are permanently “alive,” being fed from the source of electricity supply.

Thus, as contact knife 17d of the letter-plate becomes “alive,” contacts 17c of the letter plate also become “alive” and in brushing through the particular contacts 18 complete and break the circuits of the electro-magnets 11 controlling the appropriate discs 7.

To obviate lateral displacement of conveyor 15, that is arranged to run between guide pieces 21 of suitably lubricated hard wood.

A letter-plate supporting component (hitherto generally designated 16) includes (see Figs. 14 to 19, inclusively) a sheet metal plate 22 provided with side flanges 22a between which are disposed plates 23, 24 connected by a helical wire spring 25; plate 24 is fixed. Extending from said plates

are pairs of headed pins 26, 27. Said pair of pins 26—which are connected by a thumb plate 26a are adapted to move in slots 28 of plate 22 and are normally maintained in the position shown in Figs. 14, 15 and 16 through their connections with a sliding plate 23, under the influence of spring 25. Each plate 22 is pivotally pinned to the conveyor chains 15 by the aid of end flanges 22b.

The letter-plate 17 are provided with bifurcated tongue-like extensions 17e, and in applying a letter to a carrier plate one tongue of the letter is engaged with one or other of the fixed pins 27 and the other tongue is engaged with the aligned pin of the pair of pins 26 which have been outwardly displaced by hand against the spring resistance by the aid of the thumb plate 26a, and then permitted to return. This provision for enabling selection of one or other of the pairs of pins 26, 27 enables the proper spacing of the letters on the conveyor.

Referring now to the letter-plates illustrated in Figs. 20 to 22, inclusive, which are all constructed to show by way of example, the letter "E," the pin type of contacts 17a of Fig. 20 will give a lighting time substantially less than a black-out time; the plate-like contacts 17b of Figure 21 will give a longer lighting time than black-out time; and the contacts 17c of Fig. 22 will show an "E" of block type, of which the first and last vertical plate contacts only flash, the intermediate portions of the letter being continuously alight. It is to be noted that in all embodiments of my invention, the opening and closing of a sign-plate aperture is affected by a single electro-magnet and its armature.

The electric circuit controlling the operation of said discs may be as follows:

Mains alternating current is reduced by means of a step-down transformer to about 25 volts and rectified to produce direct current: the negative line of the 25 volt direct current supply is fed directly to one—say negative—side of all electro-magnets 11 of the sign: the positive line of the 25 volt direct current supply is fed to the feed line finger contact 18a carried by block 19. As a letter-plate 17 rubs through the bank of stationary contacts 18, 18a, the knife contact 17d of the letter-plate 17 engages the contact feeder line 18a and so renders the letter-plate contacts 17a, 17b or 17c, as the case may be, alive, to effect the actuation—via the particular contacts 18 connected to the other, say positive side of each of their appropriate electro-magnets 11—of the sign as selected by the letter-plate contacts.

Of course, any appropriate alternative circuit

and current supply may be utilized to effect the end in view.

I claim:

5 A luminous monogrammic sign comprising a non-transparent sign-plate provided with appropriately spaced light-emitting apertures, pivotally mounted non-transparent discs located on the inside of said sign-plate in proximity with and adapted to open and close said light-emitting apertures, electro-magnets, armatures pivotally situated below said magnets, arms associated with said pivotally mounted discs and engaged by the adjacent ends of the armatures for operatively connecting each disc with one of said armatures, 10 so that when an electro-magnet is energized its armature is caused to raise its connected disc and when the same electro-magnet is de-energized the disc is permitted to fall by gravity assisted by the weight of the pivotal armature to plate-aperture closing position, electrically illuminable tubes situated behind said plate apertures, contacts individually electrically connected with said electro-magnets, contacts for permanent connection with the source of current supply, letter members provided with a knife contact adapted 15 to engage with and disengage from the contacts connected with the source of electricity supply, simultaneously with the engagement and dis-engagement of letter member contacts, connected with said knife contacts, with and from said contacts electrically connected with the electro-magnets, according to the sign letter to be created, for energization and consequential raising of their associated discs to cause the formation of letters built up and flashed by then opened and illuminated apertures.

A. JOHNSON.
